UNITED STATES PATENT OFFICE.

ELIZABETH M. FOREHAND, OF KOKOMO, INDIANA.

SPRING ASSEMBLY.

Application filed September 17, 1923. Serial No. 663,235.

To all whom it may concern:

Be it known that I, Mrs. ELIZABETH M. FOREHAND, a citizen of the United States, residing at Kokomo, in the county of 5 Howard and State of Indiana, have invented a new and useful Spring Assembly, of which the following is a specification.

This invention relates to spring assemblies for beds, seats and all articles where spring 10 seats or backs are used.

The object of the invention is to provide a spring assembly in which the springs are independent one of the other being fastened only at the small ends leaving each free 15 from interference with other springs of the assembly producing a very flexible as well as durable assembly.

Another object is to provide an assembly 20 of this character in which repairs and replacements may be made instantly by removing the defective unit only and which is so constructed that the springs can be removed and packed in small space and reassembled with little time and effort.

25 Another object is to so construct and mount the springs that a large flat supporting surface is provided on which the mattress may rest direct without any intervening elements.

30 With the foregoing and other objects in view which will appear as the description proceeds, the invention resides in the combination and arrangement of parts and in the details of construction hereinafter described 35 and claimed, it being understood that changes in the precise embodiment of the invention herein disclosed, may be made within the scope of what is claimed without departing from the spirit of the invention.

40 In the accompanying drawings:

Figure 1 represents a top plan view of a spring assembly constructed in accordance with this invention shown used in connection with metal slats.

45 Fig. 2 is a transverse section taken on the line 2—2 of Fig. 1.

Fig. 3 is a detail vertical section showing one form of spring holder.

Fig. 4 is a similar view showing a slightly 50 different form detached.

Fig. 5 is a plan view of a combined spring holder and spacer used in connection with wooden slats; and

55 Fig. 6 is a transverse section taken on the line 6—6 of Fig. 5.

In the embodiment illustrated in Figs. 1

to 4 a spring assembly constructed in accordance with this invention for use in connection with metal slats is shown. A plurality of metal slats 1 are designed to be 60 mounted on the side rails 7 of a bed, said rails having laterally extending flanges 6 shown for supporting slats. These slats 1 each have right angularly extending flanges 2 along their side edges and are bolted at 65 their ends to slat spacers shown in the form of metal bars or straps 3 which are of any desired length according to the distance it is desired to space the slats. These straps 3 are provided at their ends with depending 70 flanges 4 which are designed to abut when in operative position as shown in Figs. 1 and 2.

Mounted to slide longitudinally on the 75 slats 1 are spring spacers 5 here shown in the form of plates having their side edges flanged as shown at 8 and provided with in-turned hooks or lips 9 along their lower edges for engaging the flanges 2 of the slats as is shown clearly in Figs. 2 and 3. 80

These plates 5 are of any suitable length according to the distance it is desired to space the springs to be carried thereby. These plates 5 are provided with upstanding collars shown at 10 in Fig. 4 and 10^a in Fig. 85 3, said collars being alike except that in Fig. 3 they are flared while in Fig. 4 the walls are straight. These collars having internal threads 11 to form sockets to receive one end of the spiral springs 12 constituting 90 a part of the assembly. The smaller ends of these springs 12 are closely coiled as shown at 13 in Figs. 1 and 3 and are designed to fit and be threaded into the sockets formed by the collars on the plates 5 so that the springs 95 will be securely connected against accidental disengagement from said plates.

The upper wider ends of the springs have 100 their final coils 14 arranged in horizontal alinement with each other to form a wide flat supporting surface the terminals 15 of said coils being hooked-shaped and bent around the adjacent coils to hold them in this position.

In the use of this device the spring holding 105 plates 5 are slipped longitudinally on the slats 1 and arranged with their adjacent ends abutting as shown in Fig. 1. The slats after the plates 5 are mounted thereon are then bolted to the spacing straps 3, the straps 110 carried by the respective slats abutting at their ends as shown in Figs. 1 and 2. The

5 springs 12 may be applied to the plates 5 either before or after said plates are mounted on the slats. These springs may be 10 quickly screwed into the sockets 10 or 10^a and when so applied form individual resilient supports for a mattress or other articles to be mounted thereon. Should one of these 15 springs be broken or bent to such an extent as to render it useless it may be quickly removed and another substituted without in any way interfering with the others.

10 In the form shown in Figs. 5 and 6 the plates 5^a are exactly like plates 5 except that they have no flanges and are designed for 15 use in connection with wooden slats on the upper faces of which they rest and are secured by screws passing through openings 16 in the ends of the plates. The collar 10^b is exactly like collar 10 shown in Fig. 4 and 20 supports a spring 12 in the same manner as do the other holders.

25 It will be obvious that while this spring assembly is primarily designed for use in connection with beds, car seats and the like it may be used wherever a yieldable cushion of this character is desired.

30 It is of course understood that the wooden slats in connection with which the holders 5^a are employed may be equipped with the spacers 3 in the same manner as are slats 1 except that screws are preferably used instead of bolts for connecting the slats with the spacers.

35 Various changes in the form, shape, proportion and other minor details of construction may be made without departing from the principle or sacrificing any of the advantages of the claimed invention.

I claim:—

40 1. A spring assembly of the class de-

scribed comprising combined spring holders and spacers, each in the form of a plate having a collar rising therefrom and threaded to receive a spring, slats on which said plates are designed to be slidably mounted, 45 said slats and plates having inter-engaging means to hold them connected, and permit them to move longitudinally relatively to each other, and spiral springs having one end closely coiled to fit the threads of said 50 collar.

2. A spring assembly of the class described comprising combined spring holders, and spacers each in the form of a plate having a collar rising therefrom and internally 55 threaded to form a socket, slats on which said plates are designed to be mounted, spiral springs having one end closely coiled to fit and screw into said sockets, and slat spacers secured to the ends of the slats and 60 extending transversely thereof and projecting on opposite sides of the slats, said spacers being designed to abut to hold the slats desired distances apart.

3. The combination with metal slats having 65 side flanges; of plates having guides along their side edges to engage the flanges of said slats, coiled springs detachably mounted on said plates and slat spacing straps secured intermediate their ends to 70 said slats and projecting beyond opposite sides thereof, said straps having their ends flanged to form abutments.

75 In testimony that I claim the foregoing as my own, I have hereto affixed my signature in the presence of two witnesses.

ELIZABETH M. FOREHAND.
